UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

PAPER-FEED MECHANISM FOR TYPEWRITERS.

Application filed August 3, 1926. Serial No. 126,904.

This invention relates to mechanism co-operating with the plate of a typewriter for facilitating feeding of the paper thereon and has for its object the provision of such mechanism which is adapted to various lengths of typewriter plateins, including those of extra lengths, and which shall be of improved construction and convenient and efficient in operation.

The invention is exemplified in the combination and arrangement of parts shown in the accompanying drawings and described in the following specification, and it is more particularly pointed out in the appended 15 claims.

In the drawings—

Fig. 1 is a fragmentary top plan view of a portion of a typewriter carriage having one embodiment of the present invention applied thereto;

Fig. 2 is a vertical section on line 2—2 of Fig. 1;

Fig. 3 is a top plan view of the paper feeding rollers and mountings therefor with parts removed;

Fig. 4 is a vertical section substantially on line 4—4 of Fig. 3; and

Fig. 5 is a vertical section taken substantially on line 5—5 of Fig. 3 but showing parts of the mechanism not illustrated in that figure.

In the embodiment of the invention illustrated, the numeral 10 designates a typewriter platen journaled in end plates 11 which are connected by links 12 to the platen carriage frame 13, the links 12 permitting vertical case shift movement of the platen. The carriage is mounted on the usual runways 14 having roller bearings 15. A shaft 16 is carried by the plates 11 and is fixed against rotation therein. Brackets 17 are fixed upon the shaft 16 and held in place thereon by screws 18.

Adjusting screws 19 are threaded in projections 20 on the brackets 17 and support compression springs 21 which supply resilient pressure for holding feed rollers 22 and 23 against the platen 10. The feed rollers 22 and 23 are supported at the ends 25 of the rocker arms 24 which are journaled on arms 26 projecting forwardly from a shaft 27. The shaft 27 is journaled in the end plates 11 and the arms 26 are provided with spaced perforated ears 28 and 29 for receiving the shaft 27. The bearing ears

28 and 29 are connected by a bridging member 30 bent over from the ear 29 which is in the same plane with the arm 26. The entire arm 26 and its connected parts are stamped from a single piece of sheet metal. 60

The shaft 27 is provided with a flattened face 31 and the perforations in the ears 28 and 29 are also flattened at one side, as shown at 32. A slightly greater segment is removed from the shaft 27 to form the bearing face 31 than the unopened portion of the perforations in the ears 28 and 29 so that a slight angular play of the arms 26 on the shaft 27 is permitted.

The upper ends of the springs 21 engage 70 lateral projections 33 on the arms 26 and press the arms upwardly to hold the rollers 22 and 23 against the platen 10. The arms 26 are held against movement along the shaft 27 by screws 34 threaded into the 75 shaft 27 and having heads of a sufficient diameter to substantially fill the space between the ears 28 and 29.

Any desired number of pairs of arms 26 can be employed, depending upon the length 80 of the platen. The rollers 22 and 23 are provided with pintles 35 at their ends which enter pivotal openings in the rocker arms 24 to permit rotation of the rollers. The rocker arms 24 are spaced from one another 85 by spacing bars 36 having pintles 37 at the ends thereof which form pivotal supports for the rocker arms 24 and which extend through openings in the supporting arms 26. The brackets 17 at intermediate points on 90 the shaft are made double, as shown in Fig. 3, and provided with two sets of projections 20, one for each arm 26 supporting adjacent ends of contiguous feed rollers. The end brackets 17 need not be double and are 95 provided with only one projection 20.

When it is desired to free the platen from the pressure of the feed rollers the shaft 27 is partially rotated in a counter-clockwise direction, as viewed in Fig. 5. This movement of the shaft is secured by a lever 38, Fig. 2, which is pivoted at 39 on the plate 11 and which carries a link 40 connected with an arm 41 secured to the shaft 27. A pin 42 cooperates with a slot 43 in the lever 38 to limit the movement of the lever. When the lever 38 is moved to its extreme forward position the pivotal connection 44 between the link and lever 40 will pass the dead center point so that the lever will 110

automatically remain in its forward position until released. This movement will compress the springs 21 and free the platen from the feed rollers. The slight lost motion between the shaft 27 and the arms 26 will permit the rollers to adjust themselves relatively to one another so that each set of rollers is subjected to its own springs and no roller is held out of contact with the platen due to any inequality in the platen itself or the mountings for the feed rollers. The pressure of the rollers can be adjusted as desired by the screws 19. The shaft 27 may be held against bending intermediate its length by braces 45 connected with the brackets 17 by the screws 18.

A deflector plate 46 is supported beneath the platen 10 for guiding the lower edge of the paper around the platen. This plate is carried by arms 47 which are mounted on the shaft 27 by means of perforated ears 48 and screws 49 in a manner similar to the arms 26. The arms 47 are freely rotatable upon the shaft 27 and are not constrained to move therewith as are the arms 26. Ears 50 on the lower face of the plate 46 are pivoted at 51 on the ends of the arms 47. Springs 52 surround the shaft 27 and bear upon screws 53 threaded in the projections 20 for adjusting the pressure of the deflector plate against the platen. The springs 52 are provided with laterally bent portions 54 for engaging the lower edges of the arms 47. The front portion of the plate 46 is shaped to fit the outer periphery of the platen, as shown at 55, and the rear edge is curved outwardly, as illustrated at 56, to receive the edge of the paper. The paper is directed between the feed roller 23 and the platen by a paper table 58 pivotally supported at 59 on the platen carriage and having a stop 60 which bears against a shaft 61 for limiting the outward movement of the paper table. Fingers 62 project downwardly from the arms 47 and underlie the projections 33 on the arms 24 so that when the arms are swung downwardly to release the paper feed rolls they will engage the fingers 62 and release the pressure of the deflector plate 55 against the platen, thus facilitating adjustment of the paper on the platen. A single deflector plate may be used for a plurality of sets of feed rollers and it is suitably recessed to permit the rollers to project through the plate to engage the platen. The finger 62 may in some cases be omitted entirely so that only the feed rollers are released when the paper is to be adjusted.

60 I claim:—

1. Paper feed mechanism for typewriters comprising a plurality of pairs of rollers for engaging the face of a platen, spacing arms pivotally supporting said rollers at opposite ends thereof, the rollers of each

pair having pivotal means journaled in their respective spacing arms and separate from the pivotal means for the rollers of the other pairs, means for pivotally supporting said arms intermediate said rollers, springs for engaging said supporting means to press said rollers against said platen, and a device common to said supporting means for compressing said springs and freeing said rollers from the pressure thereof, said device having a lost motion connection with said supporting means.

2. Paper feed mechanism for typewriters comprising a plurality of pairs of feed rollers, spacers for supporting opposite ends of the rollers of each pair, the rollers of each pair having pivotal means journaled in their respective spacers and separate from the pivotal means for the rollers of the other pairs, arms pivotally connected with said spacers intermediate the ends thereof, springs engaging said arms for forcing said rollers against the platen, a shaft on which said supporting arms are carried and with which said arms have a slight lost motion connection for rotary movement, means for holding said arms against longitudinal movement on said shaft, and means for imparting a rotary movement to said shaft to compress said springs and release said rollers.

3. Paper feed mechanism for typewriters comprising a stationary shaft extending longitudinally of the typewriter carriage, a rotary shaft arranged parallel with said stationary shaft, laterally projecting arms mounted on said rotary shaft and having perforations through which said rotary shaft extends, said perforations having flattened portions for engaging a flattened face of said shaft, said engaging portions providing a slight lost motion of rotation, a plurality of pairs of rocker arms each pivoted between its ends on one of said laterally extending arms, paper feed rollers journaled between the ends of each pair of rocker arms, springs engaging said laterally extending arms and supported by said fixed shaft for pressing said feed rollers against the platen, and means for moving said rotary shaft to compress said springs and free said feed rollers.

4. Paper feed mechanism comprising a rotary shaft, a plurality of arms mounted on said shaft, paper feed rollers carried by said arms to engage a platen, separate arms also mounted on said shaft, and a deflector plate supported by said separate arms adjacent said platen.

5. Paper feed mechanism comprising a platen, a rotary shaft arranged parallel to the axis of said platen, a plurality of laterally extending arms mounted on said shaft and each having a lost motion connection for rotation relative to said shaft, a plurality

of sets of paper feed rollers carried by said arms, a deflector plate carried by other arms freely rotatable upon said shaft, spring means for each of said arms to move the parts supported thereby toward said platen, means for rotating said shaft to release said feed rollers, and means for connecting said deflector plate supporting arms with said feed roller supporting arms to release the pressure on said deflector plate when said shaft is rotated.

6. Paper feed mechanism comprising a platen carriage having a platen journaled thereon, a shaft extending parallel with said platen and journaled in said carriage, a second shaft parallel with said first shaft and fixed on said carriage, arms mounted on said rotary shaft, rocker bars pivoted intermediate their ends on said arms, feed rollers journaled on said rocker bars, brackets on said fixed shaft, springs engaging said brackets and said arms for pressing said feed rollers against said platen, a deflector plate arranged adjacent said platen, arms pivotally mounted on said rotary shaft for supporting said deflector plate, and springs bearing upon said brackets for pressing said last-mentioned arms toward said platen.

7. Paper feed mechanism comprising a shaft, supporting arms mounted on said shaft, paper feed rollers carried by said arms, said arms having spaced bearing members connected with one another and surrounding said shaft, and screws interposed between said bearing members to prevent movement of said arms along said shaft.

8. Paper feed mechanism comprising a shaft, a plurality of supporting arms extending laterally from said shaft, rocker arms having feed rollers journaled therein, and spacer bars for said rocker arms having pintles thereon forming a pivotal connection

between said rocker bars and said supporting arms.

9. Paper feed mechanism comprising a shaft, supporting arms having lost motion connection therewith extending laterally from said shaft, rocker bars having paper feed rollers pivoted thereon, spaced bars for said rocker bars having pintles at the ends thereof extending through openings in said rocker bars and said supporting arms to provide a pivotal connection therefor, springs for pressing said supporting arms to hold said feed rollers in operating position, and means for rotating said shaft to compress said springs and free said rollers.

10. The combination with a platen carriage and a platen journaled thereon, of a fixed shaft extending parallel with said platen, a rotary shaft extending parallel with said platen, arms having a lost motion connection with said rotary shaft and projecting laterally therefrom, brackets on said fixed shaft, springs interposed between said arms and brackets, rocker bars pivoted intermediate their ends upon said arms, paper feed rollers journaled at the ends of said rocker bars, a deflector plate having the front portion thereof shaped to conform to the periphery of said platen but having the rear portion thereof spaced from the rear platen, arms pivotally connected with said deflector plate and journaled on said rotary shaft, springs for urging said arms toward said platen, means for rotating said shaft to free said feed rollers from said platen, and means for moving said deflector plate away from said platen when said feed rollers are freed therefrom.

In testimony whereof I have signed my name to this specification on this 30th day of July, A. D. 1926.

OTTO A. HOKANSON.
